UNITED STATES PATENT OFFICE.

JOHN J. SCHILLER, OF CHICAGO, ILLINOIS, ASSIGNOR TO CHARLES F. SCHILLER, OF CICERO, ILLINOIS.

EXPLOSIVE ENGINE.

Application filed November 23, 1918. Serial No. 263,817.

To all whom it may concern:

Be it known that I, JOHN J. SCHILLER, a citizen of the United States, and a resident of Chicago, in the county of Cook and State of Illinois, have invented certain new and useful Improvements in Explosive Engines, of which the following is a full, clear, and exact description.

The invention relates to explosive engines 10 and more particularly to that type in which oscillatory pistons are used.

One object of the invention is to provide an improved four-cycle oscillating engine in which power strokes are provided in substantially continuous succession so that there will be at least one power impulse for each oscillatory movement or cycle of the piston shaft. Another object of the invention is to provide an engine of this type in which the 20 gearing for driving the valve-shafts is completely located in the crank-case containing lubricant. Another object of the invention is to provide an improved engine of this type in which there is a plurality of cranks on the 25 piston shaft which are relatively offset to overcome dead centers in driving connections between the piston-shaft and the crank-shaft. Another object of the invention is to provide an engine of this type in which provision is 30 made for effective lubrication of the pistons and cylinders by lubricant in the crank-case. Other objects of the invention will appear in connection with the detail description.

The invention consists in the several novel 35 features hereinafter set forth and more particularly defined by claims at the conclusion hereof.

In the drawings: Fig. 1 is a central longitudinal section of an engine embodying the 40 invention. Fig. 2 is a transverse section taken on line 2—2 of Fig. 1. Fig. 3 is a transverse section taken on line 3—3 of Fig. 1. Fig. 4 is a transverse section taken on line 4—4 of Fig. 1. Fig. 5 is a horizontal section taken on line 5—5 of Fig. 3. Fig. 6 is a horizontal section taken on line 6—6 of Fig. 3. Fig. 7 is a horizontal section taken on line 7—7 of Fig. 3. Fig. 8 is a plan, the head and parts contained therein being removed. Fig. 9 is a vertical section with the parts disassembled.

The improved explosive engine is of the four-cycle type and comprises a casing provided with a body 15 containing two semi-cylindrical chambers 16 and 17 disposed lon-

gitudinally of one another. Each chamber is formed with straight parallel sides 18 and a longitudinally curved periphery 19. The top of each of these members extends to and is open at the top of the body 15 and is closed 60 by a head 20 which forms another part of the casing and is secured to the body 15 by bolts 99. A piston-shaft 21 is mounted adjacent the top of the body 15 and is adapted to oscillate therein. In each chamber, there is an 65 element 22, which has substantially radial heads 23 and 24, which serve as pistons, and has substantially straight sides 25 adapted to fit the straight sides 18 of said chamber and with an arcuate longitudinally curved periphery 26 adapted to fit the correspondingly curved periphery of said chamber. The pistons 23 and 24 are relatively angled, are spaced apart and divide each of the chambers 16, 17 into two arcuate working cylinders 70 on opposite sides of the piston-shaft. This form of piston-chamber provides for an efficient connection between the piston shaft 21 throughout the width of the piston and an extensive piston area. Resilient bands 75 80 are provided in the peripheral and side walls of each piston. A spark-plug 28 is provided for each cylinder. Providing two cylinder-chambers, each forming a pair of oppositely disposed working cylinders disposed longitudinally of one another, and an oscillatory piston in each of said cylinders, makes it possible to produce one power stroke during each movement of the piston-shaft and to produce power strokes for the four pistons in 85 substantially continuous succession and, as a result, there will be simultaneous intake, compression, power and exhaust strokes of the pistons in the cylinders collectively, during each movement of the oscillatory shaft in 90 95 either direction.

The body 15 is provided with a water-jacket 29 around the cylinder walls and a water-supply pipe 30 is connected to said jacket (Figs. 3, 4, and 6). Countersunk 100 bearings 32 for the piston-shaft 21 are formed in the body 15 adjacent the outer sides of the cylinder-chambers and a similar bearing 33 is formed between them. A bearing cap 34 is secured in the countersunk 105 110 bearings 32 and is extended to completely enclose the upper portion of the piston-shaft 21 independently of the head 20, so that, when the latter is removed, the adjustment of the piston-shaft will not be disturbed.

This cap also serves as a wear-member for the piston-shaft which can be replaced or adjusted. A gasket 20' is secured between the head 20 and the body 15.

5 The lower end of the body 15 is open and secured to the top of a crank-case 36 which serves as the base of the engine casing and is adapted to contain lubricant. A shaft 37 extends longitudinally through the crank-case and is mounted in suitable bearings 38 in the end walls of the crank-case. This shaft is provided with a pair of relatively offset cranks 39 and 40. Crank 39 is connected by a pitman 42 to a crank 41 on the 10 piston-shaft 21, and crank 40 on the shaft 37 is similarly connected by a pitman 44 to a crank 43 on the other end of the piston-shaft. Cranks 41 and 43 on the piston-shaft are relatively offset to overcome dead-centers. These 15 crank and pitman-connections between the oscillatory piston-shaft and the crank-shaft 37 serve to translate the oscillatory movement of the shaft 21 into rotary movement of the shaft 37 and to continuously drive the latter shaft. A fly or drive wheel 45 is secured to one end of the crank-shaft 37 and a pulley 46 for driving the usual fan-belt is secured to the other end of said shaft.

20 The head 20 of the casing contains four intake valves 48, one for controlling the supply of fuel to each of the four cylinders respectively. Each of said valves is normally closed by a spring 49, is provided with a stem 50, which is slidably held in said head and is adapted to be opened by a rocker arm 51. An intake pipe 52 (Figs. 4 and 5) is connected to a single duct 53 which is connected by branch ducts 54 with all of the intake valves. The walls of these ducts 40 53 and 54 are integrally formed with the walls of the head 20. The latter comprises a bottom wall 55 which forms the top of the cylinders and is recessed, as at 56, to fit around the cap 34 for the oscillatory piston-shaft. The intake valves 48 open 45 downwardly to deliver combustible mixture or fuel from a carburetor into the tops of the cylinders respectively. Four spring closed exhaust valves 58 for controlling the exhaust of the products of combustion from the cylinders respectively, similar in construction to the intake valves 48, are guided in the head 20. Walls 59 integral with the head form outlet ducts 60 which lead through the end walls of the head (Fig. 5) and all of these ducts are connected to a suitable exhaust manifold 61 located outside of the head. Each exhaust valve 58 is adapted to be opened by a rocker 62. The 60 space in the head outside of the duct walls forms a water-jacket 64 into which water from the water-jacket 29 in the body will flow through openings 65. A water outlet 66 is integrally formed with the top wall of 65 the head. This construction will cause the

water entering the water-jacket 29 in the body 15 to circulate through the water jacket in the head 20 and then flow out through duct 66. It will be understood that suitable circulating means, as well understood in the art, will be employed to circulate the water through these jackets.

70 Valve-operating shafts 68 and 69 which are parallel with the crank-shaft, are mounted in bearings 70 in the crank-case. Shaft 68 is provided with cams 71 for operating vertical rods 72 which are adapted to shift the rockers 51 for opening the intake and exhaust valves for the cylinders at one side of the engine, and shaft 69 is provided with cams 73 for operating similar rods 74 for operating the rockers for the intake and exhaust valves at the other side of the engine. The cam shafts 68 and 69 are driven from a pinion 75 which is fixed 80 to the crank-shaft 37. Said pinion meshes with a gear 76, to which is attached a gear 77, which meshes with a gear 78 on the cam shaft 68. The cam shaft 69 is similarly driven from the pinion 75 by a gear 80 90 to which is attached a gear 81 which meshes with a gear 82 on said cam shaft. The gears between pinion 75 and the gears on the cam-shafts are suitably supported in lugs 83 rising from a bridge 84 in the crank-case. The cranks on the crank-shaft, the cam-shafts and the gearing between the crank-shaft and the cam-shafts are all 95 enclosed in the crank-case, to effect splash lubrication of all of these parts.

100 The lower portion of the enclosing wall of each cylinder chamber is formed with a slit 86 to expose the peripheries of the pistons to the oil being splashed in the crank-case and thus the piston and cylinder will be kept lubricated. The peripheral walls between the pistons serve to close communication between the cylinders and the splash chamber and said slits permit the splash lubricant to reach the pistons. Shaft 69 is 105 provided with a cam 88 for operating an oil pump 89 to force lubricant to the bearings of the engine through suitable ducts (not shown). The bottom of the crank-case may be curved transversely, as at 94, to cause 110 the oil to drain towards the pump 89.

115 The top wall of the body 15 is cut away, as at 91, to provide clearance for the cranks on the ends of the piston-shaft, and hoods 92 and 93 are secured to said body 120 to cover said openings and to enclose the cranks on the piston shaft.

125 For convenience in description, the working cylinders of the chambers 16, 17 are designated *a*, *b*, *c* and *d* (Fig. 6). In operation, assuming a charge of compressed fuel to be present in the cylinder *a* and its piston to be at the end of its up-stroke, the charge will be ignited by the operation of the spark plug in said cylinder to impart a power 130

stroke to the piston in said cylinder, which will not only move that piston, but will operate all of the pistons and the crank shaft synchronously. During this stroke, a 5 charge will be drawn into the cylinder *b*, the charge in the cylinder *d* will be compressed and the products of combustion in the cylinder *c* will be discharged, it being understood that the cams on the cam-shafts 10 are timed accordingly. The power strokes will be imparted to the pistons in the cylinders *d*, *b* and *c* successively during successive oscillations of the piston shaft. At the end of the power-stroke in the cylinder *a*, the 15 charge in the cylinder *d* will have been compressed and will then be ignited so that the power strokes will occur in substantially continuous succession as the result of the oscillating pistons and cylinders which will cause 20 intake, compression, power and exhaust strokes to occur simultaneously in the cylinders respectively.

The improved engine thus exemplifies a multi-cylinder motor of the four-cycle type 25 and with oscillating pistons in which there is a substantially continuous succession of power strokes applied to an oscillatory shaft. During this operation, the lubricant in the crank-case will be splashed into contact 30 with a small portion of the peripheral walls between the pistons to properly lubricate them. As a result of forming the casing of the engine of a body and a crank-case containing the cam-shafts and gearing for 35 driving them and the crank-shafts, all of these parts will be effectively lubricated by the splash in said case. As the result of providing relatively offset cranks on the ends of the oscillatory piston shafts and a plurality of pitman-connections between said 40 cranks and the crank-shaft and the substantially continuous succession of power strokes, dead centers are avoided and the crank-shaft will be caused to rotate evenly 45 and continuously. As the result of providing a common head to close all of the cylinder chambers and mounting all of the intake and discharge valves in said head, so that the head can be removed from the body, 50 access may be readily had to the cylinders and the piston-shaft and pistons which can be left in its adjustment when the head is removed. By providing a removable cap for that portion of the piston-shaft which is 55 adjacent to the head 20, the latter may be removed for access to the cylinders without loosening said shaft, and furthermore, this cap provides a replaceable member between the body 15 and the head 20. The parts of

the engine are compactly arranged and the 60 gearing for driving the cam shafts, as well as the cam shaft and the crank-shaft, are enclosed in the crank-case.

The head of the casing supports and contains the intake and exhaust valves for all 65 of the cylinders, thus providing a comparatively simple construction of head for an engine, in which there is a plurality of pistons disposed longitudinally of one another on the oscillatory piston-shaft. The phrase 70 "cylinders disposed longitudinally of one another" as used in the claims is to be understood as referring to cylinders that are disposed longitudinally of the engine shaft.

The invention is not to be understood as 75 restricted to the details set forth, since these may be modified within the scope of the appended claims, without departing from the spirit and scope of the invention.

Having thus described the invention, 80 what I claim as new and desire to secure by Letters Patent, is:

1. In an explosive engine, the combination of a casing comprising a body having a plurality of parallel arcuate cylinders therein, 85 separated pistons working in said cylinders respectively, an oscillatory shaft rigid and coaxial with and operated by the pistons, the casing comprising a crank-case adapted to contain lubricant and disposed under 90 said body and the cylinders, a crank-shaft driven by the piston-shaft, disposed in the crank-case so it will splash lubricant therein, said body forming a top for the crank-case and having a restricted opening therein 95 through which lubricant will be splashed to the pistons to lubricate the cylinders, and mechanism for controlling the supply of fuel to its compression in and the exhaust from the cylinders. 100

2. In an explosive engine, the combination of a casing comprising a body having a plurality of peripheral arcuate cylinders therein, separated pistons working in said cylinders respectively, a peripheral wall closing the space between the pistons, an oscillatory shaft rigid and coaxial with and operated by the pistons, the casing comprising a crank-case adapted to contain lubricant and disposed under said body and the cylinders, 105 a crank-shaft driven by the piston shaft, disposed in the crank-case so it will splash lubricant therein, said body forming a top for the crank-case and having a restricted opening therein through which lubricant 110 will be splashed onto said peripheral wall between the pistons. 115

JOHN J. SCHILLER.
